UNITED STATES PATENT OFFICE

123,322

DESIGN FOR A COMBINED CABINET AND TABLE

Manuel Langius, Sparta, Mich., assignor to Michigan Artercraft Company, Sparta, Mich., a corporation of Michigan

Application August 22, 1940, Serial No. 94,565

Term of patent 7 years

To all whom it may concern:

Be it known that I, Manuel Langius, a citizen of the United States, residing at the city of Sparta, in the county of Kent and State of Michigan, have invented a new, original, and ornamental Design for a Combined Cabinet and Table, of which the following is a specification, reference being had to the accompanying drawing, forming a part thereof.

Fig. 1 is a perspective view of one side and one end of a combined cabinet and table with the leaves folded showing my new design, and

Fig. 2 is a perspective view of the opposite side and end of the same with one leaf elevated.

When the leaf is raised the side shown in Figure 1 is similar to that shown in Figure 2.

I claim:

The ornamental design for a combined cabinet and table, as shown and described.

MANUEL LANGIUS.
